PILE FABRIC AND METHOD OF MAKING THE SAME

Filed Oct. 17, 1929

Inventor:
Melville G. Curtis,

By *S. J. Denman*
Attorney.

UNITED STATES PATENT OFFICE

MELVILLE G. CURTIS, OF CYNWYD, PENNSYLVANIA

PILE FABRIC AND METHOD OF MAKING THE SAME

Application filed October 17, 1929, Serial No. 400,298, and in Great Britain April 9, 1929.

My invention is an improved pile fabric having the loops of the pile enmeshed or interlocked in the backing fabric or base and united thereto by a solidified pliable composition which firmly attaches the pile and reinforces the base, and may render the base impervious to moisture, without detracting from the appearance or "feel" of the nap, which projects beyond the surface of the coating composition, but may, if desired, be cut considerably shorter than is usually practicable. The adherent composition is preferably a rubber or rubber-and-glue solution, casein, or other agglutinant, and may be solidified by coagulation, vulcanization, heating or the like. Preferably the composition is substantially insoluble after solidification, and may be so colored or embossed as to give desired effects independently of or in conjunction with pile decoration resulting from printing, cutting, singeing, acid treatment or the like.

In the preferred practice of my invention, in accordance with my present improvement, the coating step is performed between the weaving and face dyeing of a double pile fabric which is woven quite loosely, with relatively few picks or weft threads over which the pile warps are looped, so that the fabrics resulting from cutting apart such double fabric would ordinarily be unsuited for dyeing, finishing or use because of the shedding of the pile fibres from the backing and the lack of firmness or body of the latter. These objections are overcome and desirable products produced, in accordance with my present invention, by impregnating the backing with a suitable adherent composition between the weaving and face dyeing of the fabric as above described. The coating forms an insoluble size preventing the dislodgment of the pile and reenforcing the backing fabrics during dyeing and minimizes bleeding from pre-dyed backing yarn into the face dye. The pile may be split to separate the backing fabrics after the composition is solidified, or the splitting may be done before the impregnation takes place. Instead of forming the pile from yarn or thread, it may be formed from filaments such as slightly twisted slivers

or rovings resulting in tufts which when cut expand or spring out to form a close pile surface.

My improvements are also adapted for the manufacture of pile fabrics by looping yarn or the like through a preformed cloth or backing and uniting the bases of the pile thus formed to the backing by cementing them in position.

The agglutinant composition may be applied to the base of the pile and to the backing in any suitable way which will leave the tips of the piles free, as, for instance, by impregnating the backing by immersion in or contact with an agglutinant after the fabric has been woven, or by coating the weft threads with a rapidly solidifying viscous agglutinant as they leave the shuttles.

After the solidification of the coating, the fabrics produced are dyed and finished and it may be decorated by cutting, singeing or acid treatment in any usual way and a background of suitable shade, texture and form provided by using an agglutinant of suitable color and composition which may produce a backing having characteristics of artificial leather or artificial silk and be suitable for embossing.

My improved product is particularly adapted for upholstery and floor coverings and a leading object of my invention is the production of a pile fabric with the pile firmly secured to a backing having a minimum number of picks or weft threads, which can be loosely, rapidly and economically woven and impregnated with the adherent composition to strengthen the backing and unite the pile base thereto while leaving the pile tips free and unaffected by backing dye. A further object of my invention is to produce a pile fabric from which the pile can be cut to form a very short nap without causing shedding.

A further object of my invention is to render practicable the utilization of rovings or slightly twisted slivers for the formation of pile. Further advantages and characteristics of my invention will appear from the following description of illustrative embodiments of my invention and the accom-

panying diagrammatic drawings in illustration thereof.

In the accompanying drawings, Fig. 1 illustrates diagrammatically a double pile fabric embodying my invention and which is being split to form pile fabric such as illustrated in Fig. 2; Fig. 3 illustrates diagrammatically a fabric embodying my improvements and having uncut loops woven therein, as in terry cloth or some types of carpet; Fig. 4 illustrates diagrammatically a split pile fabric embodying my improvements and having the piles formed of rovings or loosely twisted slivers; and Fig. 5 illustrates diagrammatically a pile fabric embodying my improvements and having the pile formed by looping yarn through a preformed backing.

As illustrated diagrammatically in Figs. 1 and 2, the double pile fabric 1 has its backings woven respectively from the warps 1, 2 and wefts 3 and from warps 4, 5 and wefts 6 and connected by pile warps 7 and 8 looped over the weft threads 3 and 6. Of course, the weaving may be done in any manner desired to form a pattern or the like by floating any of the warps at desired intervals. In order to decrease the number of weft threads and increase the output, the weft threads may be beaten up quite loosely so that the wefts are relatively widely spaced and the pile warps are but loosely bound by the engagement of the threads. The pile warps are, however, firmly fixed to the backing fabrics by an adherent composition applied to the weft threads during weaving or to the backing fabrics after weaving, and which permeates the backings so that when the composition solidifies it forms a flexible tenacious sheet or coating 9 securely embedding the looped pile threads, uniting them to the base fabrics and permitting them to be cut apart by a cutter 10, handled and dyed without shedding fibres. As shown in Fig. 2, the resultant products have their pile extending above the backing and the surface of the coating or impregnating material to form a soft nap which may be cut very short and is securely held against dislodgment.

As illustrated in Fig. 3, a single pile fabric is formed by weaving pile loops 11 around the weft threads 12 of a loosely woven backing and are secured in place by a solidifiable adherent substance 13 securely attaching the bottoms of the pile loop to the backing fabric. The outer loops may be left uncut, or may be cut by a pile wire, or by a machine in a usual manner to form a soft nap.

Fig. 4 illustrates diagrammatically a split pile fabric having the pile formed of tufted filaments 14 produced by utilizing slightly twisted slivers or rovings as pile warps. The tufts are looped over the spaced wefts

15 of a loosely woven backing and are secured in place by a solidifiable adherent coating 16, which may be applied while sufficiently fluid to impregnate the backing or may be applied in the form of an adherent sheet from which the tips of the pile project to form a close surface nap.

As illustrated in Fig. 5, yarn 17 is looped through a preformed woven or felted base 18, as in the manufacture of hooked rugs, and the base and loops are firmly united to prevent dislodgment by means of a suitable solidifiable adherent material 19 which coats and impregnates the backing fabric and the bases of the loops while leaving the upper portions of the loops soft and free to form a soft nap.

By my invention, there is obviated the necessity of providing in upholstery pluses the weft picks normally required for forming a locking support for the pile loops or for floating pile threads over several wefts, and not only is the cost of backing yarn and of weaving greatly reduced but better coverage of pile is obtained with a minimum amount of expensive face yarn. This so greatly reduces the cost of production as to permit pluses to enter the field heretofore dominated by corduroy. The invention further eliminates the difficulties heretofore experienced from the bleeding of dye into the final face-dying bath from the relatively large volume of backing threads heretofore required, and the necessity for bichromate treatment of the backing yarns to prevent such bleeding. This results in better and more uniformly dyed fabric, in a better covered fabric, in an extremely durable fabric, and in further savings in cost.

Having described my invention, I claim:—

1. In the manufacture of pile-dyed pile fabric, the steps which consist in weaving from pre-dyed yarn a pair of backings connected by pile warps, splitting the pile warps, said backings being woven too loosely for pile-dyeing the split pile without shedding thereof, and before pile-dyeing applying to the backings a composition containing rubber and forming a normally insoluble flexible composition adapted to minimize bleeding from pre-dyed yarn and secure the pile to the backings during pile-dyeing, and pile-dyeing the pile.

2. In the manufacture of pile fabric, the steps which consist in weaving a pair of backings connected by pile warps, looped over wefts of said backings, splitting the pile warps, said backings being woven too loosely for dyeing and finishing or normal use of the split fabrics without shedding pile therefrom, coating the backings with a solution containing rubber before dyeing and finishing the fabrics, vulcanizing said coatings in situ to reinforce the backings and bind the pile warps securely

thereto, and then dyeing and finishing the fabrics.

3. In the manufacture of piece dyed pile fabric, the steps which consist in weaving from pre-dyed yarn a backing having pile loops looped therein, said backing being too loosely woven for pile dyeing the pile without shedding thereof, and before pile dyeing applying to the backing a composition forming a normally insoluble flexible adherent coating adapted to minimize bleeding from the pre-dyed yarn and secure the pile to the backing during pile dyeing, and then pile dyeing the pile.

15 In testimony whereof I have hereunto set my hand this 16th day of October, 1929.

MELVILLE G. CURTIS.
